Term of patent 14 years

(Cl. D34—5)

FIGURE 1 is a top plan view of a game board showing our new design;

FIGURE 2 is a front elevation thereof taken from the plane of the line 2—2 of FIGURE 1, the rear and both side elevations being the same;

FIGURE 3 is a transverse vertical sectional view thereof on the plane of the line 3—3 of FIGURE 1; and

FIGURE 4 is a similar view thereof on the plane of the line 4—4 of FIGURE 1.

The characteristic features of our design reside in the combination on a footed game board of a series of circular depressions of contrasting color and having checkered blocks of sixteen squares outlined on each corner of the surface of the board and framing the cruciform center, with depressions located centrally in each of said checkered squares, all as shown.

We claim:

The ornamental design for a game board, as shown and described.
